PRIMARY DRY CELL

Walter R. Kempf, Lancaster, Pa., assignor to Hamilton Watch Company, Lancaster, Pa., a corporation of Pennsylvania

Application January 22, 1957, Serial No. 635,256

1 Claim. (Cl. 136—175)

This invention relates to a primary dry cell and more particularly relates to disk type primary dry cells and to a method of manufacturing the same.

In assignee's copending application Serial No. 548,660, filed November 23, 1955, now U.S. Patent No. 2,837,593 there is disclosed a disk type primary dry cell housed within a casing which consists of upper and lower shells with the periphery of the upper shell being curled about a bead at the edge of the lower shell to fasten and seal the two together. This curling operation is performed in assembly dies which contain a curling ring for curling the periphery of the upper shell about the bead on the lower shell. In the performance of this curling operation by dies of this type it has been found that a certain metal flow occurs and that this tends to deform the center portion of the upper shell and deleteriously affect the electrical connection between the upper shell and the anode which is contained therein.

According to the present invention it has now been found that this difficulty may be eliminated and a good connection between the anode and upper shell maintained, if the center portion of the upper shell is spherically domed upwards. When the assembly die is provided in a form to receive such a domed upper shell, the tendency to metal flow is diverted into another portion of the upper shell in a manner such that the electrical connection between the anode and shell is not affected. In addition, a domed anode is compressed into the domed portion of the upper shell and this anode shape results in better physical strength of the anode as it is consumed during cell drainage.

It is accordingly a primary object of the present invention to provide an improved primary cell formed of upper and lower shells and having a domed upper shell.

It is another object of the invention to provide an improved method of manufacturing disk type primary cells.

It is another object of the invention to provide an improved disk type primary cell comprised of a pair of shells wherein one shell is domed and contains a domed electrode in electrical contact therewith.

It is another object of the invention to provide an improved disk type primary cell having a domed shell portion in which a domed electrode is fitted to provide for good contact between the electrode and shell and to insure high physical strength of the electrode as it is consumed during drainage of the cell.

These and further objects and advantages of the invention will become apparent upon reference to the following specification and claims and appended drawings wherein:

Figure 1 is a vertical section showing the manufacture of a disk type primary cell according to the method herefore used; and

Figure 2 is a vertical section showing the manufacture of a disk type primary cell according to the present invention.

Referring to Figure 1, according to assignee's aforementioned copending application, a disk type primary dry

2

cell is formed from a lower shell 10 and an upper shell 12. The lower shell 10 has vertical peripheral walls 14 which are flared outwardly at 16 and provided with a peripheral bead 18. A suitable insulating gasket 20 is mounted over the upper face of the bead 18.

The upper shell 12 has an annular groove 22 concentrically located and has a depending skirt 24 which overlies the gasket 20. A suitable anode 26, which may consist of zinc powder compacted into the depression formed by groove 22 on the underside of the upper shell, engages the undersurface of the upper shell.

This cell is assembled in an assembly die consisting of an upper die member 28 and a composite lower die shown generally at 30. The upper die member 28 is provided with a recess having a flat bottom 32 and a raised circular ridge 34 which fits into the groove 22 in the shell 12. A further concentric depression 36 is provided in the upper die to receive the outer periphery of the upper shell 12.

The lower die 30 consists of a hollow cylindrical member 38 having a curling ring 40 at its upper and inner edge and having a central bore 42. A support plunger 44 is resiliently mounted in the bore 42 and supports the lower shell 10.

In the manufacture of cells by means of this assembly a cell is mounted as shown in Figure 1 and the upper die 28 moves downwardly. As the die 28 moves below the position shown in Figure 1, the skirt 24 on upper shell 12 commences to curl in curling ring 40 and is curled about bead 18 on the lower shell 10. The support plunger 44 permits the base of lower shell 10 to slide down within the bore 42 in die 30 so that no pressure is applied to this portion of the cell.

During the curling operation the upper shell resists forming and pressure is transmitted back from the bottom edge of the skirt 24 to the center of the upper shell 12. Since the shell is backed up by the punch, it cannot flex upward, but it can flex downward. Downward flexing occurs to create the space shown at 46. This downward flexing cracks the anode pellet and tends to break the bond between the pellet and the upper shell 12. When this bond is broken there is a considerable danger that a poor electrical contact between the case top and the pellet will develop thereby producing a defective cell.

Referring to Figure 2, which shows a cell assembly according to the invention, there is seen a disk type cell comprising a lower shell 48 and upper shell 50. The lower shell 48 is provided with an upstanding peripheral wall 52 having an outwardly flared wall portion 54, as described in further detail in assignee's aforementioned copending application. A bead 56 is provided at the upper edge of outwardly flared portion 54. In assembly, this lower shell 48 is carried on a resiliently mounted plunger 58 within a lower die cylinder 60 having a curling ring 62. The upper shell 50 is provided with an annular concentric groove 64, ring portion 66 and depending skirt 68. A gasket 70 is mounted over the bead 56 on lower shell 48, as described in the aforementioned copending application.

According to the invention the upper shell 50 is provided with a spherical domed central portion 72 and this is received within a mating domed recess 74 in an upper die 76. This die is provided with a suitable ridge 78 for mating with groove 64 and with a suitable annular depression 80 for receiving the ring 66. An anode 82, which may consist of powdered zinc, is compressed into the depression formed in the underside of the upper shell by the groove 64.

The two die members are brought together to curl the skirt 68 around bead 56 as described hereinabove and also in assignee's copending application. It has been found that with this particular shape of upper shell down-

ward flexure of the center of the shell is completely eliminated. Because of the strength of the dome, and further because there is no tendency to deflect downward, the center 72 of upper shell 50 does not leave the surface 74 of upper die 76 and does not interfere with the electrical contact between the anode and upper shell 50. In addition to the elimination of poor anode to shell contact during the formation of the cells, the domed shape of the upper shell is inherently stronger than the flat shape heretofore utilized and inherently resists downward deformation to a much greater degree. Because of this, it is almost impossible to unintentionally harm the electrical contact between the enclosed anode and the upper shell in normal handling of the cell. Also, the domed shape of the anode provides greater physical strength in the anode itself as the zinc is consumed during cell drainage.

The invention may be embodied in other specific forms without departing from the spirit or essential characteristics thereof. The present embodiment is therefore to be considered in all respects as illustrative and not restrictive, the scope of the invention being indicated by the appended claim rather than by the foregoing description and all changes which come within the meaning and range of equivalency of the claims are therefore intended to be embraced therein.

What is claimed and desired to be secured by the United States Letters Patent is:

A method of manufacturing a primary cell formed from a lower cup-like shell having an upstanding, peripheral wall beaded at the edge thereof and an upper cup-like shell having a depending peripheral wall and being domed outwardly at the top with a domed top contacting a domed anode received therein, comprising the steps of engaging the lower edge of said depending peripheral wall about its periphery with an annular curling die while simultaneously supporting the domed portion of said upper shell in a concave upper die and moving said dies toward each other to curl said depending peripheral wall about said bead on said upstanding peripheral wall and to cause metal flow in said upper shell to force said domed portion thereof into engagement with the concave portion of said upper die.
